THE NORRIS PETERS CO., PHOTOLITHO., WASHINGTON, D. C.

UNITED STATES PATENT OFFICE.

FRANK Y. PEARNE, OF LOS ANGELES, CALIFORNIA.

RIVETING-MACHINE.

1,305,973.

Specification of Letters Patent. Patented June 3, 1919.

Application filed January 29, 1917. Serial No. 145,301.

To all whom it may concern:

Be it known that I, FRANK Y. PEARNE, a citizen of the United States, residing at Los Angeles, in the county of Los Angeles and State of California, have invented a new and useful Improvement in Riveting-Machines, of which the following is a specification.

This invention relates to sheet metal riveting machines and more particularly to those commonly called "straight seamers" or machines for riveting the longitudinal seam of a sheet metal pipe or other cylindrical structure formed of sheet metal, and the principal object of the invention is to provide a seamer that will head the rivets of the pipe on the interior by a reciprocating tool or riveting member.

It is also an object to move the riveting member automatically from one end of the machine to the other, the rivets and the seam being securely held by a clamp acting as an anvil.

It is a further object to provide a fluid operated pressure means to operate the clamp and lap layer and also support the stake and pipe to form a rigid structure to resist the riveter.

In the drawings accompanying this specification—

30 Figure 1 is a side elevation of the machine, showing the clamp and support in open position, a portion of the stake and frame being broken away, the clutch engaged and head in riveting position.

35 Fig. 2 is a cross section on the line 2—2 of Fig. 1 showing a pipe clamped in the clamping mechanism, the head in contact with rivet, seam laid and whole supported by clamp.

40 Fig. 3 is a modification in side elevation together with the automatic mechanism for operating and moving the riveting member the latter being in lowest position, clutch disengaged and member about to be shifted to next rivet.

Fig. 4 is a cross section on line 4—4 Fig. 3 enlarged and halved to show relation of eccentric operating head, and on larger scale.

50 Fig. 5 is a layout of the sleeve cam and its relations to the fixed cam and the key for shifting the riveting carriage.

Fig. 6 is a section on the line 6—6 of Fig.

3 the position of the locking yoke being reversed or unlocked. 55

Fig. 7 is a section on line 7—7 Fig. 1 with the sliding block advanced from the position in Fig. 1; to the engaged point, and Fig. 8 is a section on line 8—8 the riveting head shown in Fig. 7 in lowest position being omitted. 60

Heretofore "straight seamers" have been operated by moving the pipe by hand, or the rivets riveted by a plurality of sliding riveting tools, mounted in a hollow stake, these tools being operated by the drawing through the stake of an inclined traveler, the latter requiring the expenditure of great force at slow speed, since the friction and pressure of heading more than one rivet at the same 70 time is enormous.

The seam and rivets have also been held by hand operated devices that are slow and cumbersome, and the length of sections necessarily limited due to a stake unsupported except at its ends. 75

My invention overcomes the above difficulties and provides a combined traveler and riveter, one head successively riveting all of the rivets automatically, as well as working 80 on one pipe during one travel and performing the same function on the return trip.

The riveting being by a stroke the power required is a minimum and the fluid operated clamping and supporting means is operated efficiently and expeditiously by toggle mechanism, the length of sections being materially increased by the intermediate supports, the length being only limited by the length of plates rolled. 85 90

More specifically, in the drawings numerals are used to designate like parts in the different views, 5 designating the base preferably, in distinction from the usual practice; being built up of two parallel 95 placed I beams, suitably bedded.

Extending upwardly from these beams is a column 6 formed of beams as shown in Fig. 3 or may be casting as in Fig. 1, secured to the base by suitable angle irons 100 7—7, upon which column the stake 8 is supported at one end.

This stake is preferably formed of two longitudinal sections, held together by suitable bolts 9 or other fasteners along their 105 lower contacting portions, the upper prox-

mate faces being grooved, or a solid stake recessed to form an open elongated channel acting as a housing and guideway for the combined riveting and traveling member, 5 with its accompanying operating shaft, the stake having flanges 10 by which it is secured to the column 6.

On the other side of the stake and supported partly in the frame of the column 6 10 is the automatic operating mechanism for moving the shaft 11 and the connected riveting mechanism, and concentrically mounted thereon and free thereon, is the large gear wheel 12 provided with one member of a 15 positive clutch, this member 14 forming the hub on one side the other having a groove by which the gear is held in longitudinal relation by the tongue 15 on the block 16.

This gear 12 is driven by a smaller gear 20 or pinion 17 keyed to a short counter shaft 18, bearings for which are provided in the column 6 and frame 19, a fly wheel 20 also fixed on the shaft being adapted to be driven by a belt continuously.

25 Next on the shaft 11 is the male member 21 under tension of the spring tension pins 22, this member of the clutch having a pair of grooves in which the roller 23 is adapted to be engaged in turn, this roller being 30 mounted on a sliding stud 24, actuated by a bell crank 25 through a connecting rod 26, the crank being under the tension of a spring 27 in the well known manner.

This member 21 slides on the shaft 11 and 35 is keyed thereto by a long key or feather 28 that is provided on its outer face with a plurality of spaced holes that determine the intermittent advance of the shaft and the riveting member in the automatic operation.

40 The frame 19 also provides a bearing for the shaft 11 exteriorly of which is the sleeve 29 that carries thereon the locking yoke 30 with the pin 31, this yoke being under the tension of the springs 32, the yoke being secured 45 to a bar 33 provided with a pin 34, the sleeve being bored and recessed to accommodate these parts, over which is secured the interior cam 35 secured to the frame 19 in fixed position.

50 On the sleeve are cut a pair of similar parallel peripheral grooves 36 and 37 that act as cams connected to receive the roller 38 mounted on a stud fixed in the movable block 39.

55 This block is provided with a hinged latch 40 and extending at right angles to engage the sides of the bracket 41 secured to the frame 19, this bracket having a pair of notches 42 into which the latch is forced by 60 a spring 43, to lock the block 39 to determine the direction of movement of the traveling member.

The yoke 30 is normally held with the pin 31 engaged in one of the holes in the key 65 28 this key being removably secured in the

shaft 11, by suitable fastenings as countersunk screws, the shaft 11 being of such length as to extend slightly outward from the sleeve 29 when the riveting carriage is at the opposite end of the stake, this latter being of such length as to rivet pipe formed of material twelve feet in length or more.

70 The riveting carriage in Fig. 1 is composed of a pair of split bearing blocks 44-45 to carry the shaft and receive the thrust of 75 the flange 46 on the shaft 11, on the other side from these blocks being the eccentric 48 adapted to reciprocate the riveting head 49, this head being held in position by a single bearing block 50, this portion of the 80 shaft being preferably of smaller diameter, and threaded to receive a washer and a retaining nut 51.

A modification of this riveting member is 85 shown in Figs. 3 and 4 in which a modified form of stake is also shown, a plate 52 forming a floor for the bearing blocks 53-54 which as in the other form closely fit within the channel and form the bearing faces for the reciprocating head 55 operated by the 90 eccentric 56 integral with the shaft 11, excepting that this form of carriage requires no thrust flange 46.

The shaft 11 is provided with a keyway in which is secured the key 28, by means of 95 screws 57 provided at its ends, the sleeve 29 and male member 21 also having keyways to receive the key.

As before stated the key is provided with a series of spaced holes, in the drawing it 100 being assumed that the three-eighths rivets are to be spaced the usual interval, or one and a half inches, which as usual are staggered so that the riveting interval is three-quarters, and as the cams throw the shaft 105 seven-eighths, the pin 31 (since the holes in the key way must necessarily be spaced the short interval or three-quarters,) will slide until it meets the next hole, and if the interval is to be greater or smaller a key with the 110 proper spacing is substituted for one in place.

To clamp the rivets and lay the lap as well as to form a sufficient support for the pipe when the traveling member is at the 115 outer end, a frame is built up from the base, consisting of the built up, upright guideways 60, in the grooves of which the slides 61, are guided, these slides being joined in pairs by fixed top frames 62 and bottom 120 frames 63 to form a rectangular slideable structure.

Intermediate of the cross frames is a slideable frame 64 and a shiftable frame 65, this latter being joined with others by a beam 66, 125 to form a rigid backing for the lap layer, clamp face and anvil 67. To permit adjustment of this clamp, the fastenings for these frames 65 may be removed and the tap screws 68 provided be secured in the holes 130

69 after the frames have been lifted by the elevating screws 70, shown as operated by hand wheels 71, the screws being threaded in the frames 62 and movably secured to 5 the end frames 65 by plates 72.

To support the entire frame when assembled, stops 73 are provided which are secured by screws or bolts 74 which may be moved to holes 75, to lower the stop 73, 10 when the largest pipe the device will carry is to be operated upon.

The two frames 63 and 64 are connected together by toggle members formed of levers 76 and 77 pivoted together by pin 78 15 with one end of lever 79, two of the latter being preferably joined by a pin 80 with the piston rod 81, fixed to a piston 82 mounted in the cylinder 83. This double acting cylinder is provided with passages 84 that 20 alternately act at opposite ends as intake and exhaust, controlled by suitable valves as 85, though all valves are preferably controlled at one station, or next the clutch operating lever 86.

25 The ends of the toggle levers are hinged in suitable blocks 108 on the respective frames 63, 64, and as described, a pair of these frames are connected by a brace 107 to form a support for the cylinder 83, and 30 since this cylinder is moved more or less, flexible couplings are necessary to connect the same to a source of fluid pressure.

For slight variations in the size of pipe 35 the blocks 87 are interchangeable to accommodate the different radius blocks 88 adapted to be secured to the sliding and contracting blocks 89 in the recesses therefor in the stake 8, under the channel, the number of 40 blocks and recesses agreeing with the number of frames, and spaced so that they co-operate therewith.

These blocks are movable to allow the pipe to be slipped on and off the stake, and to provide this movement, the blocks are 45 provided with slideways to accommodate the saw tooth arranged slides 90, these being preferably formed L shaped and secured by suitable fastenings to the stake in the recess, the blocks 88 also being secured by 50 suitable fastenings.

To slide the blocks, connecting rods 92 are threaded thereto, the first being connected to a bell crank 93 operated by a handle 94 connected with a locking quadrant 95. 55 When the blocks are in the withdrawn position as in Fig. 1 the rods 92 are housed within a groove 96 in the stake 8.

The anvil shown in the modification in Fig. 3 is not of the balanced type above described, but consists of a casting 97 supported by toggle members 98 operated by a piston rod 99 in turn connected to a piston 100 in a cylinder 101, this cylinder being supported by the beams 102, which are supported upon the column 6.

The opposite ends of these beams 102 form a support for the hanging bar 103, connected to the beams 104, which act as guide plates to the anvil 97, the stake latch 105 that supports this end of the stake, being 70 also supported upon this hanger 103.

In the operation, taking the machine as shown in Fig. 1 a pipe ready for riveting that has been punched, formed and holes alined is slipped on the stake from the right, 75 and the rivets inserted so that they project into the channel in the stake, and register with the position of the riveting head or as explained with the three quarter spacing alined. The lever 94 is now forced down to 80 draw the blocks 88 toward the lever and down to contact with the pipe as in Fig. 2, sufficient to put tension on but not to distort the pipe, and locked in this position.

Pressure from a suitable source is now introduced into the lower portions of the cylinders below the pistons 82, and the extension of the toggle members forces down the frames 63 and draws down the frames 65 through the bars 61 until the anvil rests on 90 the rivet heads and clamps the seam; the action of the continued pressure will then lift the frames 64 sliding the same upon the bars 61, until the blocks 108 contact with the bottom of the pipe; the frame lifted from 95 the stops 73 and the supporting of the stake, clamping of the pipe laying of the lap and setting of the rivets, completed. The pressure is locked by any suitable means, and the riveting begun; in practice however the head and carriage would preferably begin at one 100 end, but taking the position shown in Fig. 3 the throwing in of the clutch, after the gear 12 is driven clockwise when viewed from the stake end; by shifting the handle 86 sufficient to withdraw the pin 28, the shaft is 105 driven in the same direction and the sleeve in the direction indicated by the arrows and the roller 38 in the cam groove 36 meets the long incline and forces the sleeve locked to the shaft 11 to the right and advances the carriage one interval outwardly, and while the roller travels in the straight portion α (Fig. 5) the eccentric on the shaft forces the head to riveting position.

The pin 31 is now released by the stud 34 engaging in the cam 35 and the roller 38 traveling the portion γ in the cam shifts the sleeve on the shaft to the left seven eighths of an inch, by which time the yoke 30 is released the pin 31 under pressure and the clutch thrown out by the action of the incline 109 on the male clutch member 21, the head in its lowest position.

The roller also approximately halts opposite the gate 110 between the cam grooves so that the sleeve, shaft and riveting carriage may be shifted when it has reached the end of the riveting on the pipe. Lifting the handle 40 allows the block 39 to be shifted 125 130

to the notch, 42 ready to reverse the above travel of the head.

Pressure is now relieved in the cylinders and if necessary applied above the pistons 5 to return the frames to open position, the blocks 88 retracted by the lever 94 and the finished pipe removed.

Claims:

1. A machine of the class described, in 10 combination with a supporting frame, of a stake formed of sections provided with longitudinal grooves on their proximate faces to form a substantially hollow structure, a shaft adapted to rotate in said stake, and a 15 reciprocating riveting member adapted to be operated by said shaft.

2. A riveting machine comprising a stake support, a stake provided with a longitudinal channel, a traveling riveting carrying 20 member mounted in said channel, a riveting member, means to move said riveting carrying member, and means to operate said riveting member.

3. A riveting machine comprising a stake 25 support, a stake provided with an open longitudinal channel, into which the rivets of a pipe seam project, a traveling member in said channel, a riveting member carried by said traveling member, and means to move 30 said carrying member and operate said riveting member.

4. A riveting machine comprising a stake support, a stake provided with an open groove, an intermittent riveting member adapted to travel in said groove and head 35 rivets projecting into said groove, and means co-operating with mechanism to operate said riveting mechanism to move the same the interval of one rivet intermediate said riveting action.

5. A riveting machine comprising a stake support, a stake provided with an open groove, an intermittent riveting member adapted to travel in said groove and head rivets projecting into said groove, means 45 co-operating with mechanism to operate said riveting mechanism to move the same one interval, and reversing means to reverse said means co-operating with mechanism to operate said riveting member.

6. A riveting machine comprising a column, a stake mounted on said column, a traveling riveting mechanism, a shaft connected to said riveting mechanism, spacing means connected to said shaft to determine 55 the travel of said riveting mechanism, a cam member mounted on said shaft, means to lock said cam member in relation to said spacing means, and means to engage said cam member to shift said traveling riveting member 60 when said shaft is revolved.
